DESIGN FOR A DUSTPROOF MULTISECTION CONDENSER

Melvin V. Weiss, Haddonfield, N. J., assignor to
Radio Condenser Company, Camden, N. J.

Application January 25, 1945, Serial No. 117,600

Term of patent 7 years

(Cl. D26—1)

To all whom it may concern:

Be it known that I, Melvin V. Weiss, a citizen of the United States, residing at Haddonfield, in the county of Camden, State of New Jersey, have invented a new, original, and ornamental Design for a Dustproof Multi-Section Condenser, of which the following is a specification, reference being had to the accompanying drawing forming a part thereof.

In the drawing:

Figure 1 is a top plan view of a dustproof multi-section condenser showing my new design;
Figure 2 is a side elevational view;
Figure 3 is a bottom plan view;
Figure 4 is a front end view; and
Figure 5 is a rear end view thereof.

I claim:

The ornamental design for a dustproof multi-section condenser, substantially as shown.

MELVIN V. WEISS.
